UNITED STATES PATENT OFFICE

MONROE E. MILLER, OF WASHINGTON, DISTRICT OF COLUMBIA

DIPPER FOR SEMISOLID MATERIALS

Application filed November 5, 1926. Serial No. 146,437.

The present invention relates to dippers or scoops for dispensing ice cream or other semi-solid materials, and is particularly an improvement over the dipper disclosed in 5 my copending application Serial No. 132,869, filed August 31, 1926.

One object of the invention is the provision in combination with a top or stripping plate and scoop blades slidable downwardly 10 and upwardly relatively to said plate to be projected below and retracted above said plate, of novel means for manipulating said plate and blades in a convenient and facile manner for dipping or scooping the material from bulk and depositing same in a pail or other receptacle in a neat manner and in predetermined form and quantity.

Another object is the provision of such 20 a device having spring means so arranged that when the scoop blades are forced or thrust into the material, the top plate is under pressure to assist in packing the material.

A further object is the provision of locking means whereby the top or stripping plate and scoop blades may be locked or latched in the retracted and projected positions of the blades.

With the foregoing and other objects in 30 view, which will be apparent as the description proceeds, the invention resides in the construction and arrangement of parts as hereinafter described and claimed, it being understood that changes can be made within 35 the scope of what is claimed, without departing from the spirit of the invention.

The invention is illustrated in the accompanying drawings, wherein—

Figure 1 is a medium longitudinal section 40 of one form of dipper embodying the improvements, portions being shown in elevation and portions being broken away, with the scoop blades shown in retracted position.

Fig. 2 is a side elevation showing the scoop

blades in projected position, portions of the blades being broken away.

Fig. 3 is a fragmentary elevation of the sliding handle member or tube showing the slot therein.

Fig. 4 is a section on the line 4—4 of Fig. 2.

Fig. 5 is a section on the line 5—5 of Fig. 6 illustrating another form of dipper embodying the improvements, with modifications.

Fig. 6 is a section on the line 6—6 of Fig. 5.

Referring to Figs. 1—4, the dipper shown therein employs metal castings for some of the parts, whereas, as will hereinafter more fully appear, the other form of device illustrated is composed chiefly of sheet metal.

The top or stripping plate 7, as shown, is a casting, and is of a size and shape to correspond with that of the mouth of the pail or receptacle for which the dipper is intended. Flat scoop blades 8 of thin stiff sheet metal are slidable across the upwardly flanged edges of the plate 7 to be projected below and retracted above the lower surface of said plate. There are four blades 8 and they are tapered downwardly and of such size and shape as to conform to the walls of an ordinary ice cream pail having the shape of the inverted frustum of a rectangular pyramid, as well known in the trade, and the blades 8 slide upwardly and downwardly along straight downwardly converging lines in the inclined planes of said blades.

The plate 7 has upstanding threaded sockets or bosses 10 into which are screw-threaded or otherwise secured the upwardly diverging guide rods 12, one for each blade 8, and said rods are spaced inwardly from the margin of the plate 7 and from the blades 8. The rods 12 are parallel with the corresponding blades 8, and are connected at their upper ends by a spider or yoke 13, the upper terminals of said rods fitting in apertures in the arms of the spider and being secured therein in any suitable manner. The rods 12 and spider 13 form a rigid shank for the plate.

7, the spider 13 being cast from suitable metal.

Web plates 14, which are also castings, are provided for the upper ends of the blades, and have upstanding inclined sleeves or slides 15 slidable upwardly and downwardly on the rods 12, for guiding the blades 8 for proper upward and downward movement in their inclined planes. The plates 14 have upstanding flanges 17 overlapped by the upper ends of the blades and to which the blades are secured by rivets 18 or other securing means. The blades 8 bearing against the margin of the plate 7 will prevent the blades and sleeves or slides 15 from turning on the rods 12.

15 In order to manipulate the plate 7 and blades 8 a sliding handle member or tube 19 is slidable vertically through a central aperture in the spider 13, and has a suitable handle 20 secured on the upper terminal thereof. The tube 19 is slid downwardly and upwardly through the spider 13 for projecting and retracting the blades 8 with reference to the plate 7. For this purpose, a disk or flange 21 is screw-threaded or otherwise secured on the lower terminal of the tube 19 and is received between pairs of lugs 22 extending inwardly from the sleeves 15, thereby sliding said sleeves as well as the blades 8 upwardly and downwardly with the tube 19 and handle 20, the disk 21 being slidable in the slots between the lugs 22 when the parts move upwardly and downwardly, it being noted that the sleeves 15 move obliquely relatively to the line of movement of the tube 19.

40 A central guide rod 23 has its lower end screw-threaded into a socket or boss on the plate 7, the same as the rods 12, and projects through the spider 13 into the tube 19, to assist in guiding said tube as well as to strengthen the construction so as to prevent the tube 19 being bent or displaced transversely. If the portion of the spider 13 through which the tube 19 extends is sufficiently long, the rod 23 may be omitted.

45 In order to apply spring pressure to the plate 7 when the blades 8 are projected into the material, a coiled wire spring 24 is enclosed within the tube 19 and is confined between the upper end of the rod 23 and a cap screw 25 threaded into the upper terminal of the tube 19 over the handle 20. If the rod 23 is omitted the spring 24 may be longer so as to seat on a pin 26 that extends through the spider 13 and tube 19. Thus, when the tube 19 is slid downwardly through the spider 13 for projecting the blades 8 below the plate 7, the spring 24 is compressed and exerts downward pressure on the plate 7 so that 55 the plate is subjected to such pressure, thereby by pressing the plate 7 against the material for packing same during the dipping or scooping operation. The spring will also facilitate the retraction of the blades 8, as 60 will hereinafter more fully appear, but the

spring 24 may be omitted when the functions thereof are not wanted.

The tube 19 has diametrically opposite longitudinal slots 27 through which the pin 26 extends, thereby permitting the tube to slide longitudinally, and the ends of the slots 27 are extended transversely of the tube 19, as at 28, so that when the tube 19 is said to either completely retract or project the blades 8, the tube 19 may be turned so that the latch pin 26 enters the corresponding transverse ends of the slots, thereby locking or latching the tube 19 and spider 13 against relative longitudinal or vertical movement, which will lock or latch the plate 7 and blades 8 in the corresponding position. The ends of the slots 27 are preferably formed with notches 29 to receive the pin 26 under the influence of the spring 24 to prevent the too-free turning movement of the tube 19 when the parts are in locked or latched position.

55 The ends of the arms of the spider 13 are preferably concaved or otherwise formed, as at 30, to form finger holds in order that the spider may be held conveniently in the hand as a handle to assist in manipulating the device. As shown, the central portion of the spider is dropped or offset downwardly to provide a more compact arrangement and to permit the handle 20 to move downwardly closer to the plate 7, as seen in Fig. 2, than if the spider were located entirely in the plane of the upper ends of the rods 12.

60 In operation the handle 20 is grasped in one hand, with the blades 8 in retracted position, as seen in Fig. 1, and the device may then be readily manipulated. By turning the tube 19 so as to engage the lower ends 28 of the slots 27 with the pin 26, the handle member or tube 19 is locked to the spider 13, and the handle 20 may then be manipulated so that the plate 7 may pack the ice cream or other material down, especially if the surface of the material is irregular from previous dippings taken therefrom, and the device may also be used for pushing or scraping the material down along the sides of a can or other container. Then, by turning the handle 20 slightly to unlock or unlatch the tube 19, with the plate 7 bearing on the material, the blades 8 are readily projected down into the material by pushing the handle 20 downwardly. During this downward movement of the handle the spring 24 is compressed so as to apply spring pressure to the plate 7, in order that said plate will pack the material during the entry of the blades 8 into the material. When the blades have been completely projected into the material below the plate 7, the handle 20 may be turned slightly so that the upper ends 28 of the slots 27 engage the pin 26, which will lock the parts together, with the blades 8 projected, and the spring 24 compressed. The device may then be readily manipulated for lifting the same

from the material, and if the material does not break off even with the lower ends of the blades 8 the device may be pushed down into the material for filling the slight cavity that may exist, or surplus material below the lower ends of the blades may be scraped off. The blades containing the block or mass of material of predetermined form and size are then placed in the pail or receptacle for which the dipper is intended, and by holding the spider 13 between the thumb and fingers, this will hold the plate 7 down on the material, and by turning the handle 20 slightly, the parts are unlocked or released, so that the spring 24 will slide the tube 19 and blades 8 upwardly. This will automatically retract the blades 8 from the pail or receptacle, and the plate 7 holding the material down in the pail or receptacle will strip the material from the blades as they are retracted.

The material may also be discharged from the dipper by holding the handle 20 with the blades 8 and material above the receptacle, and by turning the handle 28 slightly so as to release the parts, the spring 24 will force the plate 7 downwardly, thereby ejecting the material from the blades downwardly into the receptacle.

The device may also be used without the spring 24, in which event the spider 13 may be held in one hand for pressing the plate 7 on the material during the dipping or scooping operation, and when depositing the material in the receptacle or pail, the spider 13 is held in one hand and the handle 20 is held in the other hand for separating said spider and handle to retract the blades 8.

Figs. 5 and 6 illustrate a different construction wherein, with the exception of the handle member or tube, handle and minor parts, the device is constructed chiefly from sheet metal or die stampings. Thus, the plate 7' and web plates 14' are of sheet metal, and the guide arms 12' which are connected at their upper ends by the yoke 13' are bent from a bar or strip of metal, and the arms 12' have the feet 10' at their lower ends riveted or otherwise secured on the plate 7'.

The scoop blades 8' are similar to those disclosed in the aforesaid copending application Serial No. 132,869, in that there are only two blades for a four-sided pail or receptacle, each blade being composed of the wings 9' arranged at a right angle with one another, and the guide arms 12' are located in such inclined positions as to be parallel to the lines of intersection of the planes of the wings 9'. The blades 8' are thus disposed astride diagonally opposite corners of the plate 7'. The web plates 14' have upturned flanges 17' to which the blades 8' are secured by rivets 18' or otherwise.

The slides 15' which are secured on the plates 14' and which move upwardly and downwardly on the arms 12' are stamped out

of sheet metal. Each slide 15' comprises the doubled brace portion 31 having the opposite doubled or bent back portions 32 fitting astride the edge portions of the arm 12', and the brace portion 31 has outstanding ears or feet 33 at its lower end riveted or otherwise secured on the plate 14'. The slides 15' are slideable freely upwardly and downwardly on the guide arms 12' so as to guide the blades 8' for proper upward and downward movement with the wings 9' moving in their inclined planes.

The handle member or tube 19' slides upwardly and downwardly through an aperture in the yoke 13', and a handle 20' is secured on the upper terminal of said tube. The connection between the tube 19' and plates 14' includes a disk 21' secured to the lower end of the tube 19', such as by means of an upstanding boss 34 on the disk secured within the lower end of the tube. The plates 14' have upstanding flanges 22' along their inner diagonal edges, and said flanges are provided with slots 35 through which the disk 21' extends, with the disk 21' overlapping the plates 14' so as to push the plates 14' and blades 8' downwardly with the tube 19'. The portions of the flanges 22' over the slots 35 extend across the disk 21' so as to raise the blades 8' with the handle, and said portions of the flanges are offset, as at 36, so as to accommodate the lower end of the tube 19' when the parts move together with the blades 8' projected.

A U-shaped or dropped bracing guide 23', formed from a bar or strip of metal, has its upper terminals secured to the yoke 13' underneath same by rivets 37 and 38 or other securing elements, and the lower intermediate portion of said guide 23' has an aperture through which the tube 19' extends. The bracing guide 23' will assist in guiding the tube 19' as well as preventing said tube from being displaced out of its axial position.

The coiled spring 24' within the tube 19' is confined between a pin 25' extending through the upper portion of the tube 19' and a pin 26' extending through the slots 27' of the tube 19'. The pin 26' is secured to the guide 23' in any suitable manner, such as by bending the ends of the pins across the edges of said guide. The slots 27' are straight from end to end so as to prevent the turning movement of the tube 19' relatively to the other parts, which will enable the dipper head to be turned in the material if desired when manipulating the dipper.

A latch or catch 28' is mounted on the yoke 13' to engage in notches 29' with which the tube 19' is provided. A finger piece 30' is secured on the yoke 13' by means of the rivet 37, as shown, and the latch 28' has an upstanding finger piece 30'' at the opposite extremity of the yoke 13' so that the finger

pieces 30' and 30" may be conveniently held between the thumb and fingers. The latch 28' has an opening 39 through which the tube 19' extends, and has a slot 40 receiving the rivet 38, so that the rivet assists in holding the latch in place. The inner end of the latch 28' is slidable under the portion 41 of the finger piece 30' which also houses a spring 42 that moves the latch 28' into the notches 29'. 19. In using the device shown in Figs. 5 and 6, the latch 28' entering the lower notch 29' will lock the parts with the blades 8' retracted, and by pressing the finger pieces 30' and 30" together, the latch 28' is disengaged 25 from the tube 19', permitting the tube to be slid downwardly toward the plate 7' for projecting the blades. When the blades have been completely projected the spring 42 moves the latch 28' into the upper notch 29', 30 to latch the parts together with the blades 8' projected. The device may then be supported by holding the finger pieces 30' and 30" between the thumb and fingers and when the blades 8' and material are placed in the 35 receptacle, pressure on the finger pieces 30' and 30" will disengage the latch 28' from the tube 19', so that the tube in being released will result in the spring 24' retracting the blades 8' from the material and receptacle. 40. The spring 24', however, may be omitted when the spring pressure on the plate 7' and spring retraction of the blades is not wanted.

In the second embodiment of the invention the finger piece or handle member 30" is 45 movable relatively to the handle 20' for latching and unlatching the parts of the dipper with the blades in either projected or retracted position, whereas in the first form of dipper shown in Figs. 1-4 the handle 20 is turned or moved relatively to the finger holds or handle portions 30 for latching and unlatching the parts, the pin 26 serving as a latch for the engagement of the tube 19.

Having thus described the invention, what is claimed as new is:—

1. A dipper comprising a top plate, a scoop blade slidable relatively to the top plate to projected and retracted positions, a yoke member attached to said top plate, a handle member slidable in said yoke member and connected to said blade, and latching means carried by the yoke member to engage the handle member.
2. A dipper comprising a top plate, a scoop blade slidable relatively to the top plate to projected and retracted positions, a yoke member attached to said top plate, a handle member slidable in said yoke member and connected to said blade, latching means carried by the yoke member to engage the handle member, and spring means between said yoke and handle members to move said blade to retracted position.
3. A dipper comprising a top plate, a scoop

blade slidable relatively thereto, a yoke member attached to said top plate, a tubular handle member slidable in said yoke member and connected to said blade, and a spring within the handle member and confined between said yoke and handle members to retract the blade. 70

4. A dipper comprising a top plate, a scoop blade slidable relatively thereto, a yoke member attached to said top plate, a tubular handle member slidable in said yoke member and connected to said blade, a spring within the handle member and confined between said yoke and handle members to retract the blade, and a latch mounted on said yoke member to engage the handle member. 75

5. A dipper comprising a top plate, guide arms secured thereto, a yoke connecting the arms, scoop blades slidable relatively to the top plate to projected and retracted positions, slides movable on said guide arms and connected to the scoop blades, and a handle member slidable through the yoke and having a connection with said slides to move therewith. 85

6. A dipper comprising a top plate, guide arms secured thereto, a yoke connecting the arms, scoop blades slidable relatively to the top plate to projected and retracted positions, slides movable on said guide arms and connected to the scoop blades, a handle member slidable through the yoke and having a connection with said slides to move therewith, and means for latching the handle member and yoke together. 95

7. A dipper comprising a top plate, guide arms secured thereto, a yoke connecting the arms, scoop blades slidable relatively to the top plate to projected and retracted positions, slides movable on said guide arms and connected to the scoop blades, a handle member slidable through the yoke and having a connection with said slides to move therewith, and means for latching the handle member and yoke together in either the projected or retracted position of the blades. 100

8. A dipper comprising a top plate, guide arms secured thereto, a yoke connecting said arms, scoop blades slidable relatively to the top plate to projected and retracted positions, slides movable on said arms and connected to the scoop blades, a tubular handle member slidable through the yoke and having a connection with the slides to move therewith, and a spring in said handle member arranged to exert pressure on the top plate when the handle member is moved toward the top plate. 115

9. A dipper comprising a top plate, guide arms secured thereto, a yoke connecting said arms, scoop blades slidable relatively to the top plate to projected and retracted positions, slides movable on said arms and connected to the scoop blades, a tubular handle member slidable through the yoke and having a connection with the slides to move therewith, a 120

spring in said handle member arranged to exert pressure on the top plate when the handle member is moved toward the top plate and tending to move the handle member away from the top plate, and means for latching the handle member and yoke together with the blades in projected position.

10. A dipper comprising a top plate, a scoop blade slidable relatively to said top plate to be projected below and retracted above said plate and having two flat wings arranged at an angle to one another and whose side edges are straight and converge toward the lower end of the blade so as to correspond with the corners at the side edges of two adjacent side walls of an ice cream or similar pail having the shape of the frustum of a rectangular pyramid, and means above said plate between said plate and blade for guiding the blade for upward and downward movement relatively to said plate along the inclined line of intersection of the planes of said wings.

11. A dipper comprising a top plate, a scoop blade slidable relatively to said top plate to be projected below and retracted above said plate and having two flat wings arranged at an angle to one another and whose side edges are straight and converge toward the lower end of the blade so as to correspond with the corners of the side edges of two adjacent side walls of an ice cream or similar pail having the shape of the frustum of a rectangular pyramid, and slidably connected handle members connected to said plate and blade above said plate to manipulate them and arranged to guide said blade for upward and downward movement along the inclined line of intersection of the planes of said wings.

40 12. A dipper comprising a top plate, a scoop blade slidable relatively to said top plate to be projected below and retracted above said plate and having two flat wings arranged at an angle to one another and whose side edges are straight and converge toward the lower end of the blade so as to correspond with the corners at the side edges of two adjacent side walls of an ice cream or similar pail having the shape of the frustum of a rectangular pyramid, said blade having a web portion between and connecting the upper ends of said wings, and means above said plate between said plate and web portion for guiding said blade for upward and downward movement along the inclined line of intersection of the planes of said wings.

60 13. A dipper comprising a top plate, blades slidable upwardly and downwardly relatively to said plate along downwardly converging lines, and upwardly diverging guiding means extending upwardly from said plate and spaced inwardly from said blades and margin of the plate, said blades having portions at their upper ends extending over said plate and engaging said guiding means.

14. A dipper comprising a top plate, inclined blades slidable along downwardly converging straight lines to be projected below and retracted above said plate, and upwardly diverging inclined arms secured to and extending upwardly from said plate and spaced inwardly from said blades and margin of the plate, said blades having portions at their upper ends extending over said plate and slidable engaging said arms.

75 15. A dipper comprising a top plate, separate blades slidable upwardly and downwardly relatively to said plate, and upwardly extending arms secured to said plate, said blades having web portions at their upper ends extending over said plate and slidable on said arms to individually guide the blades for upward and downward movement.

80 16. A dipper comprising a top plate, upwardly extending arms connected thereto, a yoke connecting said arms, and blades each slidable relatively to said plate to be projected below and retracted above said plate.

85 17. A dipper comprising a top plate, upwardly extending arms connected thereto, a yoke connecting said arms, blades slidable relatively to said plate to be projected below and retracted above said plate and having portions slidable on said arms and handle means slidable in said yoke and connected with said portions of the blades.

90 18. A dipper comprising a top plate, blades each of angular cross-section slidable relatively to said plate to be projected below and retracted above said plate, and means above said plate between said plate and blades for guiding the blades for straight line sliding movement relatively to the top plate.

95 100 18. A dipper comprising a top plate, blades each of angular cross-section slidable relatively to said plate to be projected below and retracted above said plate, and means above said plate between said plate and blades for guiding said blades along downwardly converging straight lines for sliding movement relatively to the top plate.

105 19. A dipper comprising a top plate, blades each of angular cross-section slidable relatively to said plate to be projected below and retracted above said plate, and means above said plate between said plate and blades for guiding the blades for straight line sliding movement relatively to the top plate.

20. A dipper comprising a top plate having an outline corresponding to that of the mouth of a pail having the shape of the inverted frustum of a rectangular pyramid, and two diagonally opposite blades slidable connected with said plate to be projected below and retracted above said plate, each blade being of angular cross-section and disposed astride the corresponding corner of said plate, and having flat inclined wings of a shape corresponding to those of the corresponding side walls of said pail.

115 21. A dipper comprising a rectangular top plate having an outline corresponding to that of the mouth of a pail having the shape of the inverted frustum of a rectangular pyramid, two diagonally opposite blades slidable relatively to said plate to be projected below and

retracted above said plate, each blade being of angular cross-section and disposed astride the corresponding corner of said plate, and having flat inclined wings of a shape corresponding to those of the corresponding side walls of said pail, and means between said plate and blades for guiding the blades for upward and downward movement relatively to said plate along the lines of intersection of the planes of the wings of said blades.

10 In testimony whereof I hereunto affix my signature.
